UNITED STATES PATENT OFFICE.

ALBERT R. FOSS, OF LAWRENCE, MASSACHUSETTS.

PUZZLE.

No. 922,874.

Specification of Letters Patent.

Patented May 25, 1909.

Application filed February 19, 1909. Serial No. 478,776.

To all whom it may concern:

Be it known that I, ALBERT R. Foss, a citizen of the United States, residing at Lawrence, in the county of Essex and State of Massachusetts, have invented an Improvement in Puzzles, of which the following description, in connection with the accompanying drawing, is a specification, like letters on the drawing representing like parts.

This application relates to a puzzle designed for amusement and as a test of ingenuity and patience. It is simple in construction and capable of baffling for a long time one who undertakes its solution. It involves a holder, a continuous cord passing through the holder and through a central eye mounted thereon, and carrying one or more travelers, and the object of the puzzle is to move the traveler from one loop of the cord to another.

The nature of the invention will more fully appear from the accompanying description and drawings and will be particularly pointed out in the claims.

The drawings illustrate preferred forms of the invention.

In the drawings, Figure 1 is a front elevation of a construction embodying the invention. Figs. 2, 3 and 4 are diagrammatic views illustrating the solution of the puzzle. Fig. 5 is a detail of a form of holder of slightly different construction from that shown in Fig. 1. Fig. 6 is a detail of still another form of holder.

The device comprises what is herein termed a holder A which may be made of any suitable material and which presents a longitudinal cord guide B. In the construction shown in Fig. 1 the holder may be of wood, as indicated at A, and the guide is simply a longitudinal hole bored through the wood, as indicated at B. The holder is provided with a central eye C. This eye may be fixed with relation to the holder or may rotate around it. In the construction shown in Fig. 1 the central eye C is shown as formed in a metal piece D revolvably mounted upon a reduced portion A² of the holder A.

In the form shown in Fig. 5 the holder A² is indicated as made of wire, the longitudinal cord guide being formed by the loops A⁴, while the central eye is formed by the loop A⁵. In this form the central eye is

fixed but it may be revolvable as indicated in Fig. 6.

The device also comprises an endless cord D passing through the longitudinal cord guide and formed into a loop E which passes through the central eye and is passed through by the cord, as indicated in the drawings. This endless cord may be, as indicated in Figs. 2, 3 and 4, made of a single strand, or it may be, as indicated in Fig. 1, made of a doubled strand interlooped as indicated at D². The cord carries mounted thereon one or more travelers F, each provided with an eye F². These travelers may take any form which may be desired and which may serve to add to the amusement attending the use of the device. The passing of the cord through the longitudinal cord guide in the holder is mainly for the purpose of complicating the puzzle, as the solution of the puzzle is the same whether the cord run freely through this cord guide or be fastened to the holder. Likewise the doubling of the cord, as indicated in Fig. 1, and its interlooping at D², is for the purpose of the further complication of the solution of the puzzle. Again, the construction of the piece D so that it may rotate about the holder serves further to complicate the solution of the puzzle. The solver of the puzzle will be inclined to pull the cord back and forth through the holder to manipulate the interlooped ends D² and to attempt to work the cord over and about the holder and will move the metal piece D into various rotary positions.

The object of the puzzle is to transfer a traveler, such as F, from one dependent loop of the cord extending from the end of the holder to the central eye to the other dependent loop; that is, from the position shown by the traveler at the right to the position shown by the traveler at the left in Fig. 1, or vice versa.

Referring now to Figs. 2, 3 and 4, the solution of the puzzle will appear. The holder is held in one hand, the central loop E of the cord is grasped by the fingers and pulled forwardly; the traveler F is then slid up along the cord D until it passes through the loop E, as indicated in Fig. 2; the fingers of the solver then reach through the loop E from the front and grasp the two strands of the cord D at about the points marked 2 in Fig. 2; the strands of the cord D are then

pulled forwardly through the central eye C until they pull with them the loop E and lower portions of the cord D, the said lower portions being pulled through in the form of 5 loops 3, as indicated in Fig. 3; the traveler F will then be in the position as shown in dotted lines at the left; the traveler will then be moved along the cord, through the loops 3, 3, and to the position shown in full lines 10 at the right in Fig. 3. The loops 3 will then be pulled back through the central eye 3, carrying with them the loop E, and the cord will be left substantially as indicated in Fig. 4. The traveler F will then be run along 15 the cord from its position shown in full lines to its position shown in dotted lines in Fig. 4. When the cord is now straightened out the traveler will be found to occupy the position at the right. From this description it will 20 readily be seen how the traveler can be moved back by a reversal of the operations to its former position.

The puzzle has been found to be an interesting and enjoyable one and to require much 25 patience and great ingenuity to effect its solution.

Having thus described my invention, what I claim as new and desire to secure by Letters Patent, is:

30 1. A puzzle comprising a holder provided with a longitudinal cord guide, a central eye on said holder, a traveler provided with an

eye, an endless cord passed through said guide, through said traveler eye, and formed into a loop, the said loop being passed 35 through said central eye and the cord being in turn passed through by the loop.

2. A puzzle comprising a holder provided with a longitudinal cord guide, a central eye mounted to rotate on said holder, a traveler 40 provided with an eye, an endless cord passed through said guide, through said traveler eye, and formed into a loop, the said loop being passed through said central eye and the cord being in turn passed through by the 45 loop.

3. A puzzle comprising a holder provided with a longitudinal cord guide, a central eye on said holder, a traveler provided with an eye, an endless cord having a portion inter-looped with itself to form a double endless 50 cord, the said doubled cord passing through said guide, through said traveler eye, and being formed into a loop, the said loop being passed through said central eye and the cord 55 being in turn passed through by the loop.

In testimony whereof, I have signed my name to this specification, in the presence of two subscribing witnesses.

ALBERT R. FOSS.
